UNITED STATES PATENT OFFICE.

GEORGE KETCHUM McCORD AND HORACE HERMAN SCHWARK, OF FORT WORTH,
TEXAS.

RADIATOR CAP.

Application filed August 10, 1923. Serial No. 656,646.

To all whom it may concern:

Be it known that we, GEORGE KETCHUM McCORD and HORACE HERMAN SCHWARK, citizens of the United States, and residents 5 of Fort Worth, in the county of Tarrant and State of Texas, have invented certain new and useful Improvements in Radiator Caps, of which the following is a specification.

This invention relates to radiator caps 10 especially adapted for use on automobile radiators.

Briefly stated an important object of this invention is to provide a radiator cap having simple means whereby to maintain a 15 flow of air through the upper portion of the radiator so as to carry off the heat and thereby maintain the water in the radiator cool at all times.

A further object is to provide a radiator 20 cap of the character specified which may be conveniently applied to a radiator without altering the construction of the radiator and without marring the appearance of the same and which may be cheaply manufactured.

25 Other objects and advantages will be apparent during the course of the following description.

In the accompanying drawing forming a 30 part of this application and in which like numerals are employed to designate like parts throughout the same,

Figure 1 is a perspective of the improved radiator cap applied.

Figure 2 is a vertical sectional view 35 through the same, the view also illustrating a pair of closures embodied in the invention and which may be employed in cold weather.

In the drawing wherein for the purpose of illustration is shown a preferred embodiment of the invention the numeral 5 designates a more or less cylindrical cap, the lower portion of which is offset as indicated at 6 to define an attaching portion 7. The attaching portion 7 is interiorly screw 40 threaded for engagement with the upstanding portion 8 of a radiator 9 of any desired construction. It is understood, of course, that the attaching portion 7 is of a size to correspond to the size of the upstanding portion 8 of the radiator.

50 In carrying out the invention the cap 5 is provided in opposite sides with air inlet and outlet funnels 10 and 11 respectively. The funnel 10 is uniformly enlarged toward its inlet end and may be formed in-

tegral with, or it may be secured in any suitable manner to the cap 5.

Figure 2 illustrates that the portion of the air inlet funnel 10 within the cap is extended downwardly in an inclined plane for 60 directing the air into the cap and into contact with the curved inlet elbow 14 of the funnel 11. It is very important to note that the air is not caused to discharge from the funnel 10 directly into contact with the water, but is more or less distributed and its force broken by the outlet elbow 14. This prevents the inrushing air from agitating the water in the radiator and by preventing the agitation of the water particles of the 70 water cannot be picked up by the air.

The air after circulating about and cooling 75 the water in the upper portion of the radiator enters the discharge elbow 14 of the outlet funnel 11 and the heated air is discharged to the atmosphere. Figure 2 illustrates that a baffle 16 is extended across the bottom of the elbow 14 and an opening 18 is provided in one side of the elbow 14 for the admission of the heated air. The 80 baffle 16 prevents the splashing of water through the discharge funnel 14 and it will be seen that the opening 18 faces one side wall of the cap and in fact it might be said to be adjacent the side wall opposite the air inlet funnel 10 so that the air cannot pass through the cap without first coming into contact with the water.

85 As the outlet end of the funnel 10 projects beyond the side wall of the cap and terminates adjacent the center of the cap splashing of water through the funnel 10 is prevented. Also the air moving in the direction indicated by the arrow will prevent water from passing out through the funnel 10.

90 In use the cap is applied to the radiator and the constant circulation of air through the cap and the adjacent portion of the radiator is provided for so that the overheating 95 of the radiator and the water therein is prevented.

100 In winter the funnels may be closed by caps 23 and 24 so that the water in the radiator is prevented from freezing and so that an anti-freezing liquid such as alcohol 105 cannot evaporate rapidly.

110 Attention is directed to the fact that the funnels 10 and 11 not only form air passages but also constitute bars or handholds by means of which the cap may be manually

turned so that the same will be securely held in place.

It will be seen that a comparatively large volume of air passes through the radiator cap but this air does not in any way agitate the water in the neck of the radiator. For this reason the air which is discharged from the device is not laden with an excessive amount of vapor which would condense on the hood of the automobile and on the windshield. By passing a comparatively large volume of air through the cap without agitating the water the heat extracted from the radiator by the air will be taken up by the air, but the air which is discharged from the cap will remain comparatively dry. If the water were agitated by the air the air discharged from the device would carry with it a rather high percentage of water vapor.

Having thus described the invention, what is claimed is:—

1. A radiator cap comprising a body having means whereby the same may be secured to the neck of a radiator, and an air inlet funnel secured to said body and having a discharge end terminating adjacent the center of the body, there being an outlet member arranged in the path of travel of the air entering the body whereby the force of the air is broken and whereby the air is prevented from agitating the water in the radiator cap.

2. A radiator cap comprising a body having means whereby the same may be secured to a radiator, an air inlet funnel secured to said body and having a discharge end termini-

nating adjacent the center of the body, and an air outlet funnel secured to said body and having an inlet elbow arranged adjacent the discharge end of the air inlet funnel and arranged in the path of travel of the air from the funnel to break the force of the air entering the body.

3. A radiator cap having oppositely arranged air inlet and air outlet funnels flared toward their outer ends, said air outlet funnel being provided with a discharge elbow extending downwardly and having an opening in the side thereof, said air inlet funnel terminating adjacent the center of the body and discharging the air onto said elbow, said funnels constituting attaching arms, and a baffle secured to the lower portion of said elbow and arranged in an approximately horizontal position.

4. A radiator cap having oppositely arranged air inlet and air outlet funnels flared toward their outer ends, said air outlet funnel being provided with a discharge elbow extending downwardly and having an opening in the side thereof, said air inlet funnel terminating adjacent the center of the body and discharging the air onto said elbow whereby the force of the air is broken by said elbow, said funnels constituting attaching arms, and a baffle secured to the lower portion of said elbow and arranged in an approximately horizontal position, and closures for said funnels.

GEORGE KETCHUM McCORD.
HORACE HERMAN SCHWARK.
